UNITED STATES PATENT OFFICE.

JOHN THOMSON, OF NEW YORK, N. Y.

ELECTRIC ZINC-FURNACE WITH INTEGRAL CONDENSER.

1,086,415.

Specification of Letters Patent. Patented Feb. 10, 1914.

Application filed January 2, 1913. Serial No. 739,791.

To all whom it may concern:

Be it known that I, JOHN THOMSON, a citizen of the United States, and a resident of the borough of Manhattan of the city of New York, in the county and State of New York, have invented certain new and useful Improvements in Electric Zinc-Furnaces with Integral Condensers, of which the following is a specification, reference being 10 made to the accompanying drawings, forming a part hereof.

This invention relates to the metallurgy of zinc, having for its object the production of zinc fumes by thermo-chemical reaction, 15 and then condensing the fume to liquid metal.

The particular means for attaining the desired results and such an elucidation of the general principles applicable thereto as 20 seem necessary for a complete disclosure, will be concurrently pointed out in connection with the description of the accompanying drawings, which represent certain preferred embodiments of the invention.

25 Figure 1 is a transverse center section of the furnace, viewed either right or left, as A, A¹, of Fig. 2. In this figure the lower or left hand portion illustrates one form of construction, while the upper or right hand 30 portion illustrates another form. Fig. 2 on the left hand side of its center line is a vertical longitudinal section, as on either the line B or B¹, while that portion on the right hand side of its center line is a vertical longitudinal center section, as C or C¹ of Fig. 1.

35 The class or kind of material particularly intended to be treated in this furnace (but it is not necessarily restricted thereto) is igneous oxid of zinc combined with carbon 40 as the reagent, whereby when adequately heated substantially the following representative reaction ensues, namely:

45 If pure ZnO and C are used in precisely correct relative proportions, then the answer of the above formula is an exact expression of the result in that all of the charged material would be volatilized as 50 zinc fume and monoxid of carbon, whence there would be no residue, but such conditions do not obtain in commercial practice in that more or less of inert residual matter will remain, depending upon the purity of 55 the materials employed, hence the formula becomes as stated simply: representative.

Moreover, the presence of residual matter is a cause of difficulty in realizing a successful result.

The heat necessary for decomposing the 60 charge is preferably derived from an electric current passed through a bed of carbon "resistor", the charge being placed in direct contact with the upper face thereof. Two of such resistors H, H¹, are preferably 65 employed, each being interpolated between terminals 3, to which the current is conducted by copper electrodes, 4, 4¹, and the electrification may be from separate circuits or in the same circuit either in parallel or 70 in series, according to circumstances. The resistors are preferably placed in a trough-like chamber n formed of tamped material with a sub-chamber or sump m beneath grate bars 6, upon which the resistors are 75 supported. Those portions of the tamped chamber or casing beneath and surrounding the sumps are termed hearths. The condenser J is preferably disposed midway between the resistors along the longitudinal 80 center of the furnace. It will be apparent that the condenser and either one of the resistors form an operative element or combination, regardless as to whether the other resistor is operative or inoperative or 85 whether it is in place or even removed. In this system charge material P is brought into direct contact with the upper faces of the resistors, where the primary reaction takes place, all the volatilized products 90 thereof being then caused to pass preferably directly down through the resistors, the grate-bar spaces as 7, into the sump chamber m, and thence through side openings or ports 8 directly into the receiving 95 chamber e of the condenser. If desired, however, a portion or even all of the gaseous matter may be caused to pass out of the resistors sidewise, as indicated by the port 9, Fig. 1.

100 In previous practice the charge material has been dumped upon the resistor in a considerable mass and depth, usually contained in an open shaft, which has resulted in several disadvantages, among which may 105 be mentioned the following: When oxid of zinc and particularly igneous or nearly pure ZnO is highly heated, its electrical conductivity increased, and since the reducing agent (C) which is mixed therewith is in 110 itself an excellent electrical conductor, a considerable quantity of current is, so to

5 speak, "shunted" out of the resistor into the charge, thus causing a reduction of thermal intensity at the place where intensity is most desired, namely at and in the upper 10 surface of the resistor. The reaction is thus liable to proceed more actively in some localities than others, and consequently portions of the resistor may become excessively heated and thus produce what is termed "hot spots" and also cause incrusted cavities which are frequently formed. Under such conditions fume and CO may become imprisoned and the entire face of the resistor may become coated and impregnated 15 with residual matter acting as a seal against the escape of the volatilized products of the reaction. These objections are obviated by placing a series of refractory bars or slabs as 10 across the resistors, which are 20 so set, as by means of spacing pieces 12, as to produce vertical slots or galleries 13. The bars may conveniently be supported upon the upper edges 14 of the resistor casings. The lower surfaces or edges 15 of 25 the bars may even rest upon or be in near contact with the faces of the resistors, but it is deemed preferable to provide free spaces as 16, the height of which will somewhat depend upon the thickness of the bars. 30 The charge material is fed into the said vertical galleries 13. Thus the reaction is confined to a series of transverse portions of the resistor faces, each separated by other portions, which may be of equal or less or 35 greater width and upon which no primary reaction takes place. The volatilized products are then very free to escape from the seats of the primary reaction passing in opposite directions to the free equalizing spaces 40 beneath the bars and thence downwardly into and through the resistor, as denoted by the flow arrows 17. Again, the residue is confined to the portions of the resistors immediately beneath the galleries, which may 45 considerably accumulate without sensible interference with the transfer of heat to the charge material contained in the said galleries. In this wise the resistors are in effect subdivided into transverse zones, one 50 series being for the passage of volatile matter and the other series being for the passage of inert residue. If in the primary reaction any CO₂ is formed it will be dissipated in its traverse through the incandescent resistor by a secondary reaction. If the residual ash does not percolate by gravity it 55 can be poked down into and through the resistor as by means of pointed rods operated in the slots or galleries. The passage 60 of residual matter is denoted by the flow arrows 18. The supply of charge material upon the resistors is a very simple matter, since by keeping each gallery about evenly filled a uniform rate of reaction ensues and 65 a uniform delivery of energy from the entire

surfaces of the resistors is insured. The heat imparted to the bars is not entirely lost, in fact a large proportion thereof is conducted to the charge material, which becomes progressively hotter as it descends. By using bars that are good non-conductors of electricity the "shunting" of current into the charge is eliminated, that is, to any detrimental extent. Moreover, the charge material in the galleries may be somewhat 75 tamped, compressing the ZnO and C, which is conducive to rapid reaction. This construction and arrangement is exceedingly convenient in that if repair, renewal or substitution of the resistors becomes desirable so it is simply necessary to remove the bars and thus expose the entire surfaces of the resistors. The depth of the galleries should preferably be such as to minimize heat loss by radiation from above, also to effectively 85 seal against escape of fume upwardly from the sources of reaction.

Manifestly the gaseous products delivered into the sump chamber *m* will be, so to speak, "clean" in that the temperature of 90 the resistor carbon will necessarily be maintained sufficiently high to effect a complete re-reaction upon any oxidized zinc fume and also a complete transmutation of any CO₂ to CO. 95

The ports 8 or 9 through which the volatilized products of the reaction pass to the condenser are preferably formed so as to deflect the flows upwardly against the tiles 100 20 which serve as a cover. The incoming jets 100 are thus caused to impinge upon each other and react in an upward direction upon a cooling surface, displacing the contained fume and gas from above downwardly as denoted by the flow arrows 21 and 20, subsequently thence pass through the battery of cross-stacked and alternately staggered cooling and diffusing rods 22 and 23. In this condensing system the flow through each vertical series of sinuous openings, formed 110 by the cross-stacked and staggered rods, continues uninterruptedly down and each jet of residual fume or of gas is thereby caused to directly impinge upon the zinc bath 24 contained in the bottom of the condensing 115 chamber. In the space *r* above the bath right and left hand flows are set up as the gas proceeds to the end ports 25, 26, and as the fume condensed in the rod battery must also fall down through the many openings 120 it will be apparent that a very complete intermingling and interruption of currents takes place which is conducive to condensation of a minimum of zinc fume contained in a maximum of CO gas. Finally the CO 125 passes from the ports 25, 26 into the flues or chambers T, T', and thence to atmosphere through tubes 27, 28. The reserve charge material P may be advantageously stored upon the bricks above the condenser tiles, 130

thereby serving as a seal to or from the condenser and affording a convenient source of supply to the galleries above the resistors. Obviously if desired the reserve charge material may be stored to any desired depth and to also entirely cover the bars, as denoted by the broken line P^1 .

While the bars above the resistors are shown with parallel sides, it may be advantageous to form them to a wedge-like section, the wider edges being at the top, such a construction would produce tapering galleries, widest at the bottom, somewhat less likely to become "bridged" by sintering or semi-fusing of the charge material and more readily cleared by poking bars. Assuming that the width of the feed galleries is equal to the thickness of the dividing bars, it will be seen that the surfaces of the resistors in direct contact with charge material is little more than half of the total. This, however, in no wise implies that the efficiency as a whole is diminished. On the contrary, the effectiveness of the furnace is considerably enhanced in that the intensity and constancy of the reaction along the separate zones can readily be more than doubled, for essentially all of the energy is thus available for producing reaction instead of having a portion of the total input uselessly dissipated. It is a fact indicated by theory and established by practice that more energy is required to sustain the $ZnO + C$ reaction and impart the latent heat of vaporization than to bring the charge up to the reaction temperature. The result in form of vaporized products is therefore a function derived from temperature, volume of calories and a certain period of time; hence the flow of energy to the small volume of material under intense reaction and the flow therefrom of the very large volume of gaseous product evolved must be exceedingly free to escape, and if this should fail then the efficiency of the injected energy will be materially and correspondingly diminished.

The desirable effects above set forth are realized by the principles of construction herein shown and described, which however, may be variously modified in detail, as circumstances may require, without departing from the generic and underlying features of the invention.

What I claim is:

1. In an electric zinc furnace, a bed-of-carbon resistor having overhead galleries through which the charge is fed to zones or portions of the upper face of the said resistor.

2. An electric zinc furnace having a bed-of-carbon resistor provided with overhead spaced members forming galleries or slots through which the charge is supplied to the upper face of the said resistor.

3. In an electric zinc furnace, a bed-of-

carbon resistor provided with a series of overhead spaced bars or slabs forming galleries or slots through which the charge is fed to the upper face of the resistor and free spaces at or below the lower portion of the bars to and from which the volatilized products of the reaction may enter and escape.

4. In an electric zinc furnace, a bed-of-carbon resistor provided with a series of superimposed spaced bars or slabs which produce an alternating series of transverse zones in the said resistor.

5. In an electric zinc furnace, a bed-of-carbon resistor, a series of superimposed spaced bars or slabs, a spaced grating upon which the resistor is supported, a sump chamber into which the volatilized and the inert products of the reaction flow or gravitate and openings or ports therefrom through which the fume and gas pass to the condenser.

6. In an electric zinc furnace, a bed-of-carbon resistor contained in a casing provided with openings or ports so constructed and disposed that the volatilized products of the reaction can flow therethrough without obstruction directly into the condenser after having passed through said resistor.

7. In an electric zinc furnace, a bed-of-carbon resistor contained in a casing having openings or ports leading therefrom to the condenser, the said ports being so constructed and disposed as to deflect the fume and gas upwardly against the roof or cover of the said condenser.

8. A zinc condensing chamber having therein a battery of cross-stacked and alternately staggered rods, between which the zinc fumes pass in sinuous paths, finally impinging upon a bath of liquid zinc contained in the bottom of the said condensing chamber.

9. A zinc condenser having a chamber comprising therein a battery of cross-stacked and alternately staggered rods which provide cooling surfaces and between which the zinc fumes pass in sinuous paths.

10. A combined electric zinc furnace and condenser having a battery of spaced cross-stacked and alternately staggered rods and between which rods the zinc fumes from the furnace pass downwardly in a sinuous path or paths and finally impinge upon a bath of liquid zinc contained in said condensing chamber below said rods.

11. In an electric zinc furnace a condenser arranged to receive the gaseous products of the reaction chamber, said condenser having two or more series of cross-stacked and alternately staggered members arranged so that the gaseous products will flow downwardly through spaces formed by said members.

12. An electric zinc furnace provided with

- a condenser, said condenser having therein a series of spaced cross-stacked and alternately staggered rods and a bath of molten zinc, and constructed so that the zinc fumes from the reaction chamber of the furnace can pass through the spaces between the cross-stacked rods and impinge in its transit through the condenser on the bath of molten zinc.
- 10 13. In the metallurgy of zinc, the charging of the material so as to provide spaced rows or piles of material, supplying sufficient electrically created heat to effect the reaction of the materials in the charge, the gaseous products of the reaction passing to the spaces between said rows of material and from which spaces the evolved fume can pass to a condenser, and finally condensing the metallic fumes in said condenser.
- 15 14. In the metallurgy of zinc the charging of reacting materials upon a resistor in a manner to produce spaced rows, ridges or piles, electrically heating the resistor to a temperature which will produce reaction, causing the volatilized products thereof to pass into and through the resistor between the said rows, ridges or piles, and thence to a suitable condenser.
- 20 15. In the metallurgy of zinc the feeding of a charge of substantially $ZnO + C$ to the top of a resistor so that there will not be a uniform charge over the top of the said resistor, passing an electric current through said resistor to produce a reaction of the elements composing the charge and withdrawing the fumes from the zone of reaction and passing said fumes through heated carbon and gradually and progressively condensing the fumes.

This specification signed and witnessed 49
this 31 day of December A. D. 1912.

JOHN THOMSON.
